UNITED STATES PATENT OFFICE.

SHERMAN H. PAXTON, OF HOLLAND, MICHIGAN.

DESIGN FOR A CARD-BACK.

42,876.

Specification for Design.

Patented Aug. 13, 1912.

Application filed June 11, 1912. Serial No. 703,081. Term of patent 14 years.

To all whom it may concern:

Be it known that I, SHERMAN H. PAXTON, a citizen of the United States, residing at Holland, in the county of Ottawa and State of Michigan, have invented a new, original, and ornamental Design for Card-Backs, of which the following is a specification, reference being had to the accompanying drawing, forming part thereof.

The figure is a plan view of the back of a playing card, showing my new design.

I claim:

The ornamental design for a card back, as shown.

SHERMAN H. PAXTON.
